UNITED STATES PATENT OFFICE.

JOSEPH CORNELL, OF PETERSBURG, COLORADO.

WATER-DISTRIBUTING APPARATUS.

SPECIFICATION forming part of Letters Patent No. 380,313, dated April 3, 1883.

Application filed November 8, 1887. Serial No. 234,614. (No model.)

To all whom it may concern:

Be it known that I, JOSEPH CORNELL, a citizen of the United States of America, residing at Petersburg, in the county of Arapahoe and State of Colorado, have invented certain new and useful Improvements in Water-Distributing Apparatus, of which the following is a specification, reference being had therein to the accompanying drawings.

10 This invention relates to apparatus for water-distribution; and it consists in certain improvements in an apparatus for such purpose described in Letters Patent No. 327,141, granted to me September 29, 1885.

15 In the accompanying drawings, Figure 1 is a plan view of my improved apparatus placed in the bank of a stream of water. Fig. 2 represents a longitudinal vertical section of the apparatus. Fig. 3 shows a modification in the 20 construction of the same. Fig 4 is an end elevation of the spout and its supporting-frame.

A designates a discharge-box, which is sunk in the bank of a stream in position to conduct the water therefrom to a lateral canal or ditch. 25 The discharge-box is provided with a penstock, B, having a gate, a, for shutting off the water. Adjacent to the gate a is a vertical sliding frame, C, having an opening within which is secured one end of a spout, D, which is pivoted to frame C at s, so that the spout is allowed a swinging movement, while it is retained in position by the frame. The frame and spout are further connected by a flexible web, b, forming a water-joint. The discharge 30 end of the spout is somewhat larger than the outer or inlet end extending into the stream, and an air-space, c, is provided in the upper part of the spout, vents d being provided for the admission of air to the space c.

35 E indicates a float for regulating and retaining the spout in position, being adjustably connected with a horizontal bar, F, which is movably connected with the spout by means of the coupling-blocks f and f', through apertures in which the said bar extends. The bar F is connected with the float by means of a vertical hand-screw, g, which passes through a bearing-piece, h, and slot i into the float. The bearing-piece h is journaled on bar F, to 40 allow the screw g a swaying movement.

The blocks f f' are fastened to the spout, and the aperture in the block f' is somewhat larger

in its vertical diameter than bar F, so that the outward end of the spout has a limited movement in rising or falling independent of the 55 float. To the outer end of bar F is fastened a cross-bar, k, through apertures in which, near its outer ends, extend vertical rods, the lower ends of which are connected with the float to aid in keeping it in position. The principal 60 purpose of the float is to prevent the mouth of the spout from rising above the water.

A retarding-spring, m, is connected at one end with block f', the other end of the spring being connected with sliding frame C. This 65 retarding-spring serves, as does the air-space c, in raising the spout to the extent allowed by the aperture in block f'.

G indicates bumpers secured to the sides of the spout D, and so constructed that when the 70 spout is raised by the water to the proper height these bumpers come in contact with the frame C and prevent the spout from rising higher.

The usual position of spout D being, as seen 75 in Fig. 1, at right angles with the stream, the current flows across its inlet end, and for turning water into it the spout is provided with a fixed wing, n, which is in position to effect such turning of the water that the spout 80 may be filled to the extent of its capacity.

In Fig. 3 the apparatus is shown as constructed with the penstock and spout arranged to extend up the stream and at a right-angle with the discharge-box, this form of construction 85 being preferred when the stream is narrow. With this form of apparatus two floats are used, as indicated, in connection with spout D, and the wing n is dispensed with.

By reason of the removable sliding frame C, 90 the spout may be readily detached for the purpose of repairs.

I claim—

1. In a water-distributing apparatus, a penstock, B, in combination with a vertical sliding frame, C, and an automatically-adjustable spout loosely connected with said frame, substantially as and for the purposes described. 95

2. In a water-distributing apparatus, in combination with a sliding frame, C, an adjustable spout 100 provided with bumpers G and loosely connected with said frame, substantially as set forth and described.

3. In combination with a penstock, B, an

adjustable spout loosely mounted in front of the penstock and provided with coupling-blocks f and f' , an adjustable coupling-bar, F, extending through apertures in said blocks, 5 and a float adjustably connected with said bar by means of a vertical screw, substantially as set forth and described.

4. In combination with the sliding frame C, the spout D, connected therewith and provided

with air-space c, having vents d, bumpers G, 10 and a retarding-spring, m, substantially as set forth, for the purposes specified.

In testimony whereof I have affixed my signature in presence of two witnesses.

JOSEPH CORNELL.
